(57) **CLAIM**

The ornamental design for a USB device, as shown and described.

DESCRIPTION

FIG. 1 is a front perspective view of a first embodiment of a USB device according to the invention.

FIG. 2 is a front view of the USB device of FIG. 1.

FIG. 3 is a rear view of the USB device of FIG. 1.

FIG. 4 is a right side view of the USB device of FIG. 1.

FIG. 5 is a left side view of the USB device of FIG. 1.

FIG. 6 is a top plan view of the USB device of FIG. 1.

FIG. 7 is a bottom plan view of the USB device of FIG. 1.

FIG. 8 is a rear perspective view of the USB device of FIG. 1.

FIG. 9 is a front perspective view of a second embodiment of a USB device according to the invention.

FIG. 10 is a front view of the USB device of FIG. 8.

FIG. 11 is a rear view of the USB device of FIG. 8.

FIG. 12 is a right side view of the USB device of FIG. 8.

FIG. 13 is a left side view of the USB device of FIG. 8.

FIG. 14 is a top plan view of the USB device of FIG. 8.

FIG. 15 is a bottom plan view of the USB device of FIG. 8; and,

FIG. 16 is a rear perspective view of the USB device of FIG. 8.
